UNITED STATES PATENT OFFICE.

DAVID M. SNYDER, OF ABINGDON, ILLINOIS, ASSIGNOR OF ONE-FOURTH TO
FRANK S. MARSHALL, OF ABINGDON, ILLINOIS.

RAILROAD-SIGNAL.

SPECIFICATION forming part of Letters Patent No. 724,347, dated March 31, 1903.

Application filed June 23, 1902. Serial No. 112,865. (No model.)

To all whom it may concern:

Be it known that I, DAVID M. SNYDER, a citizen of the United States, residing at Abingdon, in the county of Knox and State of Illinois, have invented a new and useful Railroad-Signal, of which the following is a specification.

This invention relates to railway-signals, and has for its object to produce an improved apparatus for signaling at railway-crossings to give timely warning of approaching trains, the apparatus being so constructed that it will be operative only on the side of the crossing from which the train is approaching and will be inoperative by the train after it has passed the crossing, so that the trains will not sound or display a signal after they have passed the crossing.

The invention consists in a trip mechanism adapted to be engaged by the passing train and so connected to the signaling mechanism that it will operate the signal when the train is going in one direction only.

The invention further consists in two or more trip mechanisms located at opposite sides of the signal mechanism and at opposite sides of the crossing and so constructed and connected as to be operative only when the train is approaching the crossing and not operative by the train after it has passed the crossing.

The invention further consists in certain novel features of the construction, as will be hereinafter described, and specified in the claims.

In railway signal apparatus arranged to be operated at railway-crossings it is important that the signals shall be actuated only while the train is approaching the crossing, so that persons about to cross the tracks will know when the signal is sounded or displayed that a train is approaching and not leaving the crossing; and the principal object of the invention which is the object of the present application is to produce a simple, easily-installed, and operative device which will work accurately, promptly, and with certainty and which will operate when the train is approaching from either direction.

The signaling apparatus will be located adjacent to the crossing at a point adapted to

warn approaching passengers, while the tripping mechanism will be located at points sufficiently remote from the crossing to give timely warning of the approaching train.

In the drawings illustrative of the invention, Figure 1 is a side elevation of sections of a railway-track with portions broken out and with the improved signaling apparatus connected therewith. Fig. 2 is a plan view of the same. Fig. 3 is an enlarged side view; and Fig. 4 is a plan view, on the same scale, of the trip mechanism. Fig. 5 is a perspective view, on a smaller scale than Figs. 3 and 4, of the signaling apparatus detached.

The device may be applied to any construction of railway, either steam or electric, and in the drawings a section of a railway-track consisting of the usual rails 10 and 11 and ties 12 is shown.

The signal apparatus as a whole will necessarily cover a sufficient distance or length of the railway-track, so that ample notice shall be given of approaching trains, and this distance will generally be from one thousand to two thousand feet on each side of the railway-crossing, these distances being governed somewhat by the circumstances and the conditions of the road-bed or the objects adjacent to the crossing.

The apparatus is applicable to all the conditions and circumstances adjacent to the crossing and is adapted to all the varying conditions usually met with in such localities.

In the drawings, Figs. 1 and 2, the rails and signal connections are shown in sections, illustrating the fact that the total length of the parts sought to be illustrated are very much longer than the parts actually shown, as will be understood.

No attempt is made to show the crossing of the railway-tracks, as this forms no part of the present invention, and the arrangement is so well understood as not to require illustration.

The signaling mechanism is supported upon a base 13, extending at right angles to the rails 10 and 11 to any suitable distance and will be located adjacent to the crossing at one side, while the first or nearest trip mechanism will be located some hundreds of feet from the signal mechanism at one side of the

crossing, while the opposite trip mechanism will be located on the opposite side of the crossing some hundreds of feet therefrom. A series of these trip mechanisms will be located some distance apart in both directions from the crossing, the number corresponding to the circumstances of the road-bed and the objects adjacent to the crossing.

The signaling apparatus consists of a standard 14, rising from the base 13 and extended over at its upper part and provided with a gong or bell 16. Movable supported upon the base 13, adjacent to the standard 14, are two standards or striker-arms 17 18, movably supported at their lower ends, as at 19, to the base 13 and provided with spring hammer-arms 21 22, adapted to cause balls 23, carried by their upper ends, to strike the gong 16 when the standards 17 18 are forcibly vibrated. The standards 17 18 are connected by rods 23 24 to bell-crank levers 25 26, pivotally supported at 27 28 to the base 13, adjacent to one of the rails 10 or 11, as the case may be. The rods 23 24 will be provided with turnbuckles 29 30, by which their lengths may be adjusted. The bell-crank levers will be retained in place by a strap 31 and will be held normally in their open position by springs 32 33. By this means the springs 32 33 will cause the rods 23 24 to return the arms 17 18 to their normal position when the bell-crank levers are released, as will be herein-after explained. The rods 23 24 will be suitably supported longitudinally by a bracket 32, and in localities where it is necessary to prolong the base 13 a series of these brackets 32 will be employed, so that the gong and its supports and hammer-bars 17 18 may be located at any desired distance from the tracks. The standard 14 may be made of any height and the bars 17 18 of corresponding height, according to requirements of the location where it is erected.

The trip mechanism is illustrated more fully in Figs. 3 and 4 and, as before stated, will be located at suitable points upon each side of the crossing and as many of the trip mechanisms employed as may be required. These trip mechanisms are all precisely alike, so that like denoting characters will be employed for each. Each of the trip mechanisms will be provided with a base 33, suitably supported adjacent to one of the rails, preferably outside the rails, but which may be under certain conditions located between the rails. The base-plate will be properly secured, preferably by being connected above the ties 12 or to a separate foundation, as may be required. Supported upon the base-plate are two spaced longitudinal bars 34 35, being attached to the base-plate, preferably, by feet 36 37 and bolts 38 39, as shown. Vertically arranged between the bars 34 35 is a trip-plate 41, the trip-plate being pivotally supported between the bars by a transverse stud 42 and with an aperture 43 formed in

its lower part, the aperture being elongated and the trip-plate made wider at its lower end to provide for the elongated aperture. The upper end of the trip-plate 41 preferably projects above the "head" of the adjacent rail 10 or 11, as the case may be, and will preferably be located close to the head of the rail, so as to be engaged by the treads of the pilot-wheels of the locomotive-truck and also by the treads of the other wheels of the train, so that each wheel of the train will successively engage the trip-plate as the train passes over them, and where a number of the trip-plates are arranged at intervals all the wheels of the train on one side will engage all of the trip-plates successively, as will be understood.

Instead of arranging the device so that the treads of the wheels will engage the trip-plates a series of contact bars or rollers may be arranged upon the train to engage the trip-plates, and I do not, therefore, desire to be limited to the use of any specific part of the train or to any specific attachment thereto for engaging the trip-plates, as many different parts of the train, either of the running-gear or of the bodies of the locomotive or tender or coaches or cars, may be employed for the purpose of operating the trip-plates.

Supported in a suitable bearing 44 upon the plate 33, opposite the vertical central line of the trip-plate 41, is a rock-shaft 45, having an arm 46 on its inner end and a similar arm 47 on its outer end, the arm 46 having a stud 48 extending into the aperture 43, as indicated. Supported upon the base 33 at one side of the longitudinal bars 34 and 35 is a bearing 49, supporting another rock-shaft 50, having arms 51 52 extending from its ends, respectively, as shown. The arm 52 is connected to the arm 47 by a connecting-rod 53, while the arm 51 is connected to the inner end of the crank-arm 26 or 25, as the case may be, by a rod 54. The stud 48 when the trip-plate 41 is in its normal vertical position, as shown in Fig. 3, will engage the end of the aperture 43 nearest to the signaling mechanism supported upon the base-plate 13, as indicated in Figs. 1 and 2. The trip-plate 41 will be maintained normally and yieldably in its vertical position by a spring 55, which exerts its force constantly downward upon the trip-plate and will permit it to be moved to the right or left when force is applied to its upper end, as when a car-wheel engages it, as will be readily understood.

It will be noted that if the car-wheel strikes the trip 41 from the direction of the arrow in Fig. 3 the upper end of the trip-plate will be moved over to the right and cause the stud 48 to be moved to the left, thus rotating the rock-shaft 45 correspondingly and depressing the arm 47 and causing the rod 53 to rotate the rock-shaft 50 and cause the arm 51 to draw the rod 54 toward the trip-plate, and thus actuate the crank-arms 25 26, as the case may be, and sound the gong or bell 16,

through the rods 29 or 30 and hammer-arms 17 18, as the case may be, or according to which direction the train may be moving.

The studs 48 will be located in the end of 5 the slots 43 nearest to the signal mechanism, no matter on which side of the latter they may be located, so that the arms 46 and 47 will always be extended toward the signaling apparatus—that is to say, all of the mechanisms upon the right-hand side of the signal mechanism will be so arranged that their respective arms 45 46 will be extended to the left or toward the signal mechanism and all the mechanism upon the left-hand side of the 15 signal mechanism will be so arranged that their respective arms 45 46 will be extended to the right or toward the signaling mechanism. By this arrangement it will be evident that by reason of the studs 48 fitting the 20 elongated slots 43 and engaging the slots by one end only when the trip-plates are moved from the opposite side or from the side toward the signal mechanism the trip-plates will not effect the studs, but will move over them without operating them. It will be thus understood that when the train is moving toward the signal mechanism it will act upon the trip-plates in the direction of the 25 arrows shown in Fig. 3 and actuate the signal mechanism, but will not affect the signal mechanism when moving in the opposite direction. It will also be understood that by 30 locating the trip mechanisms upon each side of the signal mechanism they will cause the signal mechanism to be operated only when the train is approaching the crossing and will not be operated when the train is leaving the crossing.

The coupling-wires 54 will be attached by 40 their ends successively to the arms 51, so that if any one of the trip-arms be depressed or moved toward the signal apparatus the latter will be operated, and the face of all the trip-arms upon each side of the crossing being coupled together by the rods 54 will not interfere with their co-operative or independent action, as the rods will simply move the trip-arms to a certain extent when any one or more of the trip-arms are depressed without detriment to the operation of the apparatus.

To insure a sufficient degree of flexibility to the apparatus to prevent undue or unequal strains, coiled springs 55 will be inserted into 55 the rods 54 between each pair of the arms 51, so that the latter will yield sufficiently to prevent breakage. The arms 51 will each be provided with a spring 56 to assist in retaining the parts in their proper normal operative 60 position and to restore them to their proper places after each action.

The different structures supported upon the base-plate 33 will be detachably connected thereto, so as to be readily removed for 65 pairs or renewal.

The spring-arms 21 22 serve an important function, as they prevent a too-rigid connec-

tion between the balls or hammers 23 and the arms 17 18, thereby securing the necessary yieldable action between the gong and the 70 sounding-hammers.

Beneath the plate 33 opposite the trip-arm 41 is arranged a casing 57, into which the trip-arm projects and which affords a support for the lower end of the spring 55, so that the 75 trip-arm and spring have ample room for their necessary movements.

The turnbuckles 29 30 serve an important purpose, as they enable the parts to be properly adjusted, so that their action upon the 80 levers 17 18 will be of just sufficient strength to cause the hammers 23 to act with the proper force upon the gong 16. By this simple structure the gong 16 is sounded when the first 85 wheel of the "pilot-truck" of the locomotive 85 engages the most remote of the trips 41 on the side of the crossing from which the train is approaching and the gong sounded successively as each of the trips in the series on that side is engaged by each of the wheels of 90 the train, so that a continuous series of signals is sounded until the last wheel of the train has passed the nearest trip-arm to the crossing, while at the same time the train in leaving the crossing on the opposite side will 95 simply pass over the trip-arms without causing them to affect the signals. This is a very important feature of the invention, as the person approaching the crossing when he hears the signals will know that a train is approaching and will not be deceived or misled as he might be if the signal mechanism were so arranged as to be sounded both when the train is approaching and leaving the crossing.

The different parts of the apparatus may 100 be made of any required size and adapted to withstand the severe strains to which they will be subjected by the rapidly-running trains striking the trip-plates. All of the parts will preferably be of steel, except the gong 16, and will be of proper proportions to each withstand the strains to which it will be subjected, and the trip-plates, as before stated, may be located at any desired distance from the crossing and with any desired distance between the individual trip mechanisms, these distances, as before stated, depending somewhat upon the conditions adjacent to the crossing.

Where the crossings occur near to heavy 105 cuts or where obstructions obscure the view of approaching trains, the trip mechanisms will be arranged comparatively close together, so as to sound the signal at frequent intervals, and thus give a more noticeable warning, as in such localities railway-crossings are the most dangerous. On the other hand, in open countries where the view is unobstructed for a long distance the distances between the individual tripping mechanisms might be increased and the number of separate trips decreased; but it will be understood that I do not wish to be limited to any specific number of the tripping mechanisms or to their dis-

tances apart or to their distances from the crossings, as the device is adapted to be modified to enable it to be employed under all the different conditions and in the different localities where such a device is required.

Having thus described my invention, what I claim is—

1. In a railway-signal, a base-frame, spaced longitudinal bars detachably connected to said base-frame, a trip-plate movably supported by said bars and having an elongated aperture, a main rock-shaft movably connected to said base-plate and having an arm on its inner end movably engaging said aperture and with an arm extending from its outer end, a supplemental rock-shaft supported movably upon said base-plate and having arms extending from its opposite ends, a spring connected to said supplemental rock-shaft arm and adapted to normally support it in operative position, a rod connecting said outer arm on said main rock-shaft with one of the arms of said supplemental rock-shaft, a signal mechanism, and means connecting said signal mechanism with the other of said supplemental rock-shaft arms, substantially as described.

2. In a railway-signal, a base-frame, spaced longitudinal bars detachably connected to said base-frame, a trip-plate movably supported by said bars and having an elongated aperture, a main rock-shaft movably connected to said base-plate and having an arm on one end movably engaging said aperture and with an arm extending from its outer end, a supplemental rock-shaft supported movably upon said base-plate and having arms extending from its opposite ends, a rod connecting said outer extended arm on said main rock-shaft with one of the arms of said supplemental

rock-shaft, a signal mechanism, and connecting means between the other of said supplemental rock-shaft arms and said signal mechanism, substantially as described.

3. In a railway-signal, spaced longitudinal members, a trip-arm movably supported between said longitudinal members in position to be engaged by the passing trains and provided with an elongated aperture, a rock-shaft carried by said frame and having an arm on one end engaging one end of said aperture, an arm extending from the opposite end of said rock-shaft, a signal mechanism, and means connecting said signal mechanism with said extending arm, substantially as described.

4. In a railway-signal, a supporting-frame having spaced longitudinal members, a trip-arm movably supported between said longitudinal members in position to be engaged by the passing trains and provided with an elongated aperture, a rock-shaft carried by said frame and having an arm on the inner end engaging one end of said aperture, and with an extended arm on the outer end, a supplemental rock-shaft having extended arms on its ends, a rod connecting one of said extended arms with the outer arm of said main rock-shaft, a signal mechanism, and operative means between said signal mechanism and the other of said supplemental rock-shaft arms, substantially as described.

In testimony that I claim the foregoing as my own I have hereto affixed my signature in the presence of two witnesses.

DAVID M. SNYDER.
